UNITED STATES PATENT OFFICE.

JOHN A. MILLER, OF CHICAGO, ILLINOIS.

TRUSS STRUCTURE.

Application filed May 5, 1921. Serial No. 467,011.

To all whom it may concern:

Be it known that I, JOHN A. MILLER, a citizen of the United States, and a resident of Chicago, in the county of Cook, State of Illinois, have invented certain new and useful Improvements in Truss Structures, of which the following is a specification.

My invention relates to truss structures, the object being to produce built-up wooden truss structures which are particularly adaptable and efficient for supporting roofs over extended floor areas, as for example, in dancing pavilions, skating pavilions, auditoriums, coliseums, garages, etc., where a floor of considerable area is to be covered and kept free from pillars, posts or other obstructions to sight or movement. A further object is to provide such simple construction and arrangement that ordinary stock lumber and hardware supplies can be utilized and the truss structures readily and accurately built up on the spot where a building is to be erected, an entire truss structure or span being completed on the ground and then raised into position on suitable piers provided therefor.

My improved truss structure is clearly represented on the accompanying drawing in which

Fig. 1 is a side elevational view of a truss structure showing it raised in place on its supporting piers,

Fig. 2 is an enlarged side elevational view of a section of the truss structure and

Fig. 3 is a sectional view on plane 3—3 of Fig. 2.

The truss structure shown comprises the outer arch member 10 and the inner arch member 11 which may have any desired curvature. As shown, these members are in greater part along the arc of a circle and are parallel. The inner arch member continues downwardly to the piers 12 anchored in the ground, while the upper arch member at its ends 10' deflect laterally and slightly downwardly to be supported on the upright beams 13 which rest on the pillars or piers 12 alongside of the ends of the inner arch member 11. The arch members are spaced apart and between the main portion thereof, in this case the parallel circular portion, are inserted spacing members designated as a whole by S. The arch members are of laminated construction. The upper arch member is built up of boards 14 which overlap and are securely held together

by spikes or other fastening devices 15. The lower arch member is also laminated and built up of overlapping boards 16 secured together by spikes 17. The arch members are built up on the ground, suitable template or other guide arrangement being provided so that the arch members will assume their proper curvature. The spacing members S comprise each an upper block 18 and a lower 60 similar block 19, the blocks being placed edge to edge as clearly shown in Figs. 2 and 3. The blocks at their ends are beveled so as to increase the contact surface of their outer edges with the respective arch members 65 without materially increasing the weight of the spacing members. The spacing members can be inserted after formation of the arch members or, the inner boards of the arch members can first be spiked or otherwise secured to the blocks and the outer laminations then secured one to the other by spikes or otherwise until the arch members have been built up to the required thickness. After building up of the upper and lower arch 70 structures they are brought together with the inner edges of the blocks in register and then bolts 20 are applied which extend entirely through both arch members and the blocks as clearly shown. To insure proper 75 alignment of the blocks and also to strengthen the arch members against relative longitudinal shift after bolting together thereof, the blocks may be provided with dowel notches 21 for receiving the dowel pins 22. 80

Between the lower ends of the lower arch member and the deflected ends 10' of the upper arch member the space is considerably increased and between these ends and the uprights 13 lattice work or brace members 23 95 are secured which extend at the proper angle to give the greatest strength. With this increased space between the ends of the arch members and the uprights 13 together with the brace members a very strong and rigid 100 end structure is provided for the truss which will prevent collapse at the weakest point. The uprights 13 also constitute a support for a side wall of the building supported by the trusses so that entrance and exit can be 105 more conveniently provided. The deflected ends 10' of the upper arch structure when extended beyond the upright 13 also form wide eave supports 24 for sheltering people along the outside of the building, and if 110 necessary, braces 25 may be provided for these eave sections.

If desired, extensions 26 may form part of the truss structures, these extensions being secured at their inner ends to the truss structure and deflect laterally a distance above the body of the structure to leave space 27 in which ventilating devices or windows may be placed when the building is constructed. These extensions can also be laminated and formed up of boards overlapping and nailed 10 or otherwise secured together.

As before stated, the truss structures are built up complete on the ground, and are then raised up and set on the spiers 12 provided therefor, the ground then acting as a 15 chord to hold together the ends of the truss structures to prevent separation thereof. This arrangement is particularly adaptable for low buildings such as dance pavilions or other pleasure buildings. In higher buildings chord members would be provided and 20 extended between the ends of the truss structures.

The truss structure of my invention is extremely simple, yet very rigid and efficient 25 and capable of supporting considerable loads. The laminated arch members together with the spacing blocks and bolts and the expanded braced ends of the structure provide this great strength and rigidity. Ordinary stock boards and ordinary hardware 30 is used for securing the parts together and thus the cost is materially reduced. No skilled carpenter work is required, the ordinary spacing blocks taking the place of the more complicated brace bars of prior structures which require greater skill in forming 35 and fitting. Furthermore the blocks afford much greater contact area with the arch members than ordinary brace bar construction, such extended contact area serving to 40 increase the strength and rigidity of the arch members. Buildings have been constructed in which the truss span is over one hundred feet with a vertical thickness at the center of the truss of less than three feet. I do not desire to be limited to the precise 45 construction and arrangement shown as modifications are possible which would still come within the scope of the invention.

50 I claim as follows:

1. In a truss structure, the combination of outer and inner arch members each built up of laminations in the form of boards, blocks secured at their outer edges against each of said arch members, the inner edges of said blocks registering, and bolts extending through said arch members and blocks.

2. In a truss structure, the combination of outer and inner arch members each formed of laminations of boards rigidly secured together, blocks secured at their outer edges against each of said arch members, the inner edges of said blocks registering, bolts 60 extending through said arch members and

blocks, and dowel pins inserted between the engaging edges of said blocks.

3. In a truss structure, the combination of outer and inner arch members, a row of spacer blocks applied on edge against the inner side of the outer arch member, said member being composed of laminations in the form of boards rigidly nailed together and to said blocks, a row of blocks set on edge on the upper face of the inner arch member and said member being composed of laminations in the form of boards secured together and to said blocks, the inner edges of said blocks registering, and bolts extending through said arch members and said blocks. 75

4. In a truss structure, the combination of outer and inner arch members, a row of spacer blocks applied on edge against the inner side of the outer arch member, said member being composed of laminations in the form of boards rigidly nailed together and to said blocks, a row of blocks set on edge on the upper face of the inner arch member and said member being composed of laminations in the form of boards secured together and to said blocks, the inner edges of said blocks registering, bolts extending through said arch members and said blocks, and dowel pins inserted between the engaging edges of said blocks. 80

5. In a truss structure, the combination of outer and inner arch members, spacing members each comprising an outer block and an inner block extending parallel with the arch members, the outer blocks being independently secured to the outer arch member at spaced intervals and said inner blocks being independently secured to the lower arch member at correspondingly spaced intervals whereby when said arch members are brought together said blocks will engage and register at their inner edges, and bolts extending through said arch members and registering blocks to rigidly secure said members and blocks together to form the truss structure. 95 100

6. In a truss structure, the combination of outer and inner arch members, spacing members each comprising an outer block and an inner block extending parallel with the arch members, said blocks being of frusto-conical longitudinal cross section, the outer blocks being independently secured to the outer arch member at spaced intervals with their bases or outer edges against the member and said inner blocks being independently secured to the inner arch member at correspondingly spaced intervals and with their faces or outer edges against said inner member whereby when said arch members are brought together, corresponding blocks will engage and register at their inner edges, and bolts passing through said arch members and registering blocks to rigidly secure said members and blocks together to form the truss structure. 115 120 125 130

7. In a truss structure, the combination of an outer arch member and an inner arch member, sets of outer and inner spacing blocks extending longitudinally and interposed between said arch members at spaced intervals with their outer edges against the arch members and with their inner edges engaging and registering, and bolts extending through said arch members and registering blocks to rigidly secure the arch members and blocks together to form the truss structure.

8. In a truss structure, the combination of outer and inner arch members, sets of spacing blocks extending longitudinally and interposed between said arch members with their outer edges against said members and their inner edges in engagement and registration, dowel pins between the blocks of each set, and bolts extending through said arch members and registering blocks, said bolts rigidly securing said arch members and blocks together to form the truss structure and said dowel pins preventing longitudinal displacement of said blocks and said arch members.

9. In a truss structure, the combination of outer and inner arch members each built up

of over-lapping boards secured together, said arch members being parallel and spaced apart only a short distance in comparison with their length, spacing members in the form of short lengths of plank inserted between the members, said spacing members being placed centrally between the sides of the arch members and extending longitudinally thereof and parallel with the arch members, and bolts extending through the arch members and through the spacing members.

10. In a truss structure, the combination of an outer arch member and an inner arch member parallel therewith, said members being spaced apart a short distance as compared with their length, spacing members in the form of short lengths of plank set on edge between the arch members and extending longitudinally thereof and with their upper and lower edges in intimate contact throughout their lengths with said arch members, and bolts extending through said arch members and said spacing members.

In witness whereof, I hereunto subscribe my name this 29th day of April, A. D. 1921.

JOHN A. MILLER.
